US00D906654S

(12) United States Design Patent (10) Patent No.: US D906,654 S
(45) Date of Patent:  Jan. 5, 2021

(54) FOOTWEAR BOTTOM

(71) Applicant: Fuerst Group, Inc., Menlo Park, CA (US)

(72) Inventors: Mark Faulconer, Newport Beach, CA (US); Chris Brown, Portland, OR (US)

(73) Assignee: FUERST GROUP, INC., Menlo Park, CA (US)

() Term: 15 Years

(21) Appl. No.: 29/693,345

(22) Filed: May 31, 2019

(51) LOC (13) Cl. 02-04

(52) U.S. Cl.

USPC D2/953; D2/951

(58) Field of Classification Search

USPC ..... D2/902, 906, 908, 916, 918, 925, D2/946-962, 972, 977; 36/3 B, 22 R, 36/24.5, 25 R, 28, 32 R, 34 R, 59 C, 36/67 A, 103

(57) CLAIM

The ornamental design for a footwear bottom, as shown and described.

DESCRIPTION

The sole FIGURE is a plan view of a footwear bottom according to the claimed design.

The relative depths and three dimensionality between the surfaces of the footwear bottom form no part of the claimed design.

1 Claim, 1 Drawing Sheet
